GAS-WASHING APPARATUS

Alfred J. Ebner, Pittsburgh, Pa.

Application June 10, 1950, Serial No. 167,297

8 Claims. (Cl. 261—90)

1

This invention relates to apparatus for washing gases, and more particularly to the hot and dirty gases of blast furnaces, open hearths and other metallurgical furnaces, and other industrial apparatus that produce dirty gases.

In Letters Patent No. 2,163,141, granted to me June 20, 1939, I illustrate and describe a gas-washing apparatus that comprises two impellers, mounted concentrically one within the other. The inner impeller is fixed to a driven shaft, while the outer impeller is journaled for free or "floating" rotation upon the shaft. The impeller assembly is housed within an involute chamber, into which an inlet opens for the gases to be washed. A liquid, such as water, or light oil, or ammonia, or hot tar, or the like, is delivered into the housing by means of pipes or nozzles, and, by the action of the rapidly driven inner impeller, the injected liquid is converted into a fine spray. The dirty or raw gas which is forced or drawn through the inlet into the impeller chamber is subjected to the scrubbing action of the impeller blades or vanes, and is brought into intimate contact with the finely divided droplets of the washing liquid, which pick up and retain the particles of dust and condensed vapors or fumes in the raw gases. The impellers exert under centrifugal force the liquid particles and their inclusions against the walls of the impeller housing, whence they drain to the bottom of the housing for removal to a suitable receptacle for disposal or further processing. The clean gases are delivered from the housing by way of an outlet passage opening tangentially from the involute chamber therein.

Due to the high temperature of the gases, the erosive dust and the corrosive fumes that are included with the gases entering the apparatus, the problem has been to provide bearings for the impellers which will endure the heat and the abrasive effects of the inclusions in the gases. My present invention consists in a particularly effective bearing structure that affords a solution of the problem.

The invention will be understood upon reference to the accompanying drawings, in which:

Fig. 1 is a view in side elevation of a gas-washing apparatus that embodies the invention;

Fig. 2 is a view of the apparatus partly in vertical medial section, and partly in elevation, as seen from the left of Fig. 1; and

Fig. 3 is a fragmentary sectional view, illustrating a modification in the structure in which the invention is centered.

Referring to the drawings, the reference numeral 1 indicates a housing including a central involute chamber 2. The opposite side walls of

2

the housing carry bearings 3, 3 for the shaft 4 of an impeller or vaned rotor 5. The impeller 5, rigidly fixed to the shaft 4, is centered with respect to the involute chamber 2, as appears in Fig. 2. Encompassing the impeller 5, and mounted concentrically with respect thereto, is an outer rotor or impeller 6. The inner impeller 5 is driven by means of an electric motor or other prime mover (not shown) connected to the shaft 4, while the outer impeller 6 is free to rotate under the reaction of the fluids propelled by the inner impeller 5.

The bearings for the shaft 4 comprises two bearing elements, in this case in the form of two blocks 10 which are severally secured in the tubular housings 11 of the bearings 3, 3. The casings 11 of the bearings are mounted in fluid-tight assembly on the side walls of the housing 1, and at the outer end of each bearing casing a packing gland 12 is arranged to seal the shaft.

While the inner impeller 5 is positively driven, as described above, the outer impeller 6 is mounted for independent or free rotation, the mounting for the outer impeller comprising bearing elements in the form of hubs or bushings 13, formed of hard rubber or other suitable bearing material, secured in casing portions 14a that extend inwardly from the side walls of the housing 1. Spacer rings 14 are mounted on the shaft 4, between the hub of the inner rotor 5 and the hubs of the spiders 8 of the outer rotor, thus insuring proper axial centering of the inner and outer impellers.

The impeller 6 comprises a pair of spiders, each having a hub portion 7, from which spokes 8 radiate in spaced relation. To the outer ends of the arms or spokes 8 of each spider an annular plate 9 is secured. At uniformly spaced-apart points in the circumference of the annular plates 9, 9 two rows of rods 15 and 16 span the interval between such plates. On these rods three sets of annular plates 17 and 19 are mounted. The annular plates 9, 17 and 19 appear in dotted lines in Fig. 1, while the showing of such plates in Fig. 2 is conventionalized for clarity of illustration. The inner set of plates 17 is centered or aligned with the vanes or blades 18 of the inner impeller 5, which in turn is centered with the involute chamber 2, while the other two sets of annular plates 19, are arranged on opposite sides of the central set 17. The plates 17 and 19 are secured in their illustrated spaced relationship (Fig. 2) upon the rods 15 and 16, say by welding, or by the use of spacer sleeves arranged on the rods between the adjacent plates. The assembly is held together by means of nuts threaded on the ends of the rods

15 and 16 extending through the outside annular members 9, 9. It will be perceived that inner set of plates 17 are more closely spaced than the two outer sets of plates 19; that the inner set of plates is of greater radial extent than the outer sets; and that additional rods 25 reinforce the assembly of the inner set of plates. Between the plates 17 of the inner set arcuate vanes 20 are mounted at intervals uniformly spaced circumferentially of the rotor assembly, as appears in Fig. 1.

The entrance for the fluid to be propelled comprises two inlets 21, mounted symmetrically on opposite sides of the involute chamber 2, and opening into the housing 1 in the regions in which the vanes 17 are located. This will be understood upon reference to Fig. 2, in which one of such inlets 21 are shown. An outlet 22 opens tangentially from said involute chamber. The gases entering the apparatus through inlets 21 are drawn to the center of the rotating inner impeller 5, whence they are propelled by centrifugal force into the spaces between the plates 17. Through inlets 23 provided in the opposite side walls of the housing 1, a gas-washing liquid is jetted upon the rapidly rotoring blades of the impeller 5, and by the impact of such blades the liquid is converted into a spray. The gas being propelled through the apparatus is subjected to a violent scrubbing action by the impeller blades, and is brought into intimate contact with the liquid in finely divided form. The liquid droplets pick up the dust or other particles to be removed from the gases, and the gases with the liquid droplets are propelled into the passages between the plates 17, and against the surfaces of the vanes 20 between such plates. Under the reaction of the gases and water globules impelled against the vanes 20, the impeller 6 is rotated. Clean gas escapes from the outer edges of the plates 17 into the involute chamber 2, whence it escapes through the outlet 22. The droplets of washing liquid with the inclusions removed from the gases drain to the bottom of housing 1, whence the accumulated liquid is removed through outlets 24.

Velocity and energy are imparted to the liquid and gases by the rotating blades of the impeller. The vanes 20 between the plates 17 are impinged upon by the gases and liquid delivered by impeller 5 across the breadth of the set of plates 17, and the impact of the gases and liquid against such vanes supplements the scrubbing accomplished by the impeller 5. The two outer or lateral sets of blades 19 are effective to maintain the gases entering the apparatus distributed laterally of the spaces in the housing 1 on opposite sides of the impeller 5, and to provide for a distributed flow of the entering gases on the opposite sides of such impeller, whereby a distributed and uniform supply of the gases is drawn into the impeller.

In accordance with the invention the bearings 3,3 are designed to exclude the gases in the impeller housing 1 from contact with the relatively moving wearing surfaces of the bearing elements, whereby freedom is obtained from any abrasive or corrosive action of the dust particles or vapors entrained in the gases. More particularly, a fluid under pressure—a gas-washing liquid in this case—is forced between the bearing surfaces inwardly into the housing 1, with the effect that not only is the desired exclusion of gases obtained, but the bearings are efficiently cleansed, cooled and lubricated.

Into each bearing casing 11 an inlet 35 opens 75 surface 71 of the rotating hub and the inner end

on the outer side of the bearing element 10, and through such inlet a suitable liquid such as light oil, or an emulsion of oil and water, or other suitable liquid, is delivered under a pressure exceeding that of the gases within the housing 1. This liquid flows inwardly between the contacting surfaces of the bearing element 10 and the rotating shaft 4, and through passages 26 formed in the body of bearing 10 into an annular space 27. The passages 26 conveniently consist in a plurality of axially extending circumferentially spaced slots, which insure a distributed movement of liquid within and around the entire body of the bearing element. From the space 27 the liquid is forced inwardly between the relatively moving contact surfaces of the brushing 13 and hub 7 of the rotor 6. Upon reaching the inner end of the bearing casing 11 the liquid escapes from between the relatively rotating surfaces of the said bushing and hub, where it is entrained with the gases rapidly moving under the propulsion of the impeller 5. From the space 27 there is also a flow of the liquid inwardly between the surface of the shaft 4 and the bore in the hub 7 and upon emerging from the bore of the hub the liquid works its way between the spacer rings 14 and the shaft 4. Under the effect of the rapidly rotating shaft the rings 14, rotating under the frictional drag of the shaft, operate as slingers; that is, the liquid, seeping between the adjacent lateral surfaces of the rings 14, as it does, is thrown centrifugally into the gases moving rapidly into the orbit of the blades of impeller 5. The blades beat the liquid into a spray, and such spray operates with the liquid introduced through openings 23 in the cleansing or washing of the gases in the manner already described. Indeed, in some cases the injection of liquid through the bearings 3,3 may be increased to the extent that all liquid required for washing the gases will be obtained through the bearings 3,3 without introducing any liquid through the inlets 23.

Fig. 3 illustrates a modification in the structure of the bearings 3,3 wherein the bearing element or bushing 30, the bushing 130 and the hub 70 are arranged concentrically one within another.

Each of the two hubs 70 of the outer rotor or impeller 6 provides in the modified structure a bearing for the shaft 4, and each hub carries an external bushing or journal 130 for rotation in the associate bearing casing 11, the bearing element 30 providing a liner or inner bushing in the hub, with which the rotating shaft 4 makes immediate bearing contact. A circumferentially spaced series of passages or grooves 260 is formed within the shaft-engaging surface of the bearing element 30, and through these grooves the liquid fed into the bearing under pressure flows along the shaft, providing bearing lubrication and excluding the infiltration of gases and dust from within the housing 1. Upon emerging from the grooves 260 the liquid flows into the spaces 140 formed in the bodies of the spacer rings 141, whence it seeps between the laterally abutting surfaces of the rings and is thrown outward into the streaming gases on their way into the zone of action of the impeller 5.

The bushing 130 may be provided with a circumferential series of grooves 131, through which the liquid flows to the inner end of the bearing casing 11, whence it works its way between the

(11a) of the said casing, and emerges into the turbulent gases within the housing 1.

The structure of the invention solves the problem alluded to in the introduction to this specification, and affords many advantages which will be apparent to those skilled in the art. And it will be understood that many variations in the form and arrangement of the structure described may be made without departing from the spirit of the invention defined in the appended claims.

I claim:

1. Gas-washing apparatus comprising a housing having an inlet and an outlet for the gas to be cleaned, inner and outer impellers mounted concentrically of each other in said housing, a horizontal shaft rotatably supporting the inner impeller, with the outer impeller mounted for "floating" rotation about the shaft, each of said impellers having a hub portion, the hub portions of the two impellers being spaced apart axially of the shaft, a plurality of spacer rings mounted on the shaft between said hub portions for maintaining the impellers in alignment longitudinally of the shaft, a bearing for said shaft comprising a bearing casing sealed to the wall of said housing, a bearing element in said casing for said shaft, a passage in said bearing structure communicating at one end with the surface area of the shaft encompassed by said spacer rings, and means for admitting liquid to said passage at a higher pressure than that of the gas prevailing in said housing, whereby liquid delivered inwardly through said passage is thrown centrifugally into the gas in said housing by the action of said spacer rings rotating with said shaft.

2. Gas-washing apparatus comprising a housing having opposite side walls and including an inlet and an outlet for the gas to be cleaned, inner and outer impellers mounted concentrically of each other in said housing, a horizontal shaft rotatably supporting the inner impeller, said outer impeller being supported by spiders including hubs mounted on said shaft on opposite sides of said inner impeller, said inner impeller having a hub portion on said shaft, bearings for said shaft on opposite sides of impeller assembly, each bearing comprising a bearing casing sealed to the side walls of said housing, said hubs of the outer impeller comprising bearing elements arranged in said bearing casings, a bearing element in each of said casings for said shaft, passages in each bearing assembly communicating with the surface areas of the shaft encompassed by said spacer rings on opposite sides of the inner impeller hub, and means for admitting liquid to said passages at a higher pressure than that of the gas prevailing in said housing, whereby liquid delivered inwardly through said passages is, by the action of said spacer rings rotating with the shaft, thrown centrifugally into said housing for movement into gas-scrubbing cooperation with said impellers.

3. Apparatus for propelling a gas that includes an abrasive or corrosive material comprising a housing having an inlet and an outlet for the gas to be propelled, two impellers mounted concentrically one within the other in said housing, a horizontal drive shaft, spider means supporting one impeller, the other impeller being secured to said shaft, a bearing assembly for said shaft comprising a casing sealed to the wall of said housing, two bearing portions arranged one within the other to said casing, one bearing portion for said shaft and the other for said spider means, each bearing portion having passages communicating with the interior of said housing.

and means for admitting bearing-cleansing fluid under pressure to said passages, whereby such fluid is caused to cool and lubricate said bearing portions and to escape into the gas propelled through said housing.

4. Apparatus for propelling a gas that includes an abrasive or corrosive material comprising a housing having opposite side walls and including an inlet and outlet for the gas to be propelled, two impellers mounted concentrically one within the other in said housing, a horizontal drive shaft, spider means supporting one impeller, the other impeller being secured to said shaft comprising two casings sealed one to each of the opposite side walls of said housing, two bearing portions arranged one within the other in each casing, one of said two bearing portions in each casing providing a bearing for said shaft and the other for said spider means, each of said bearing portions having passages communicating with the interior of said housing, and means for admitting bearing-cleansing fluid under pressure to said passages, whereby such fluid is caused to cool and lubricate said bearing assemblies and to escape from said assemblies toward the opposite sides of said concentric impellers that propel said gas through said housing.

5. The structure of claim 4, said impellers being located between said bearing assemblies, and a plurality of spacer rings mounted on the shaft between the impellers and bearing assemblies, said passages being arranged to deliver said liquid to said spacer rings, whereby liquid delivered inwardly through said passages is thrown centrifugally by said rings into the gas propelled through said housing.

6. Apparatus for propelling a gas that includes an abrasive or corrosive material comprising a housing having an inlet and an outlet for the gas to be propelled, two impellers mounted concentrically one within the other in said housing, a horizontal drive shaft, spider means supporting one impeller, the other impeller being secured to said shaft, a bearing assembly for said shaft comprising a casing sealed to the wall of said housing, a hub portion extending from said spider means into said casing concentrically of the shaft, a bushing secured within said hub portion to provide a bearing for said shaft, with the shaft-engaging surface of the bushing formed with passages communicating with the interior of said housing, a bushing secured externally upon said hub to provide in conjunction with said casing a bearing for said spider means, with passages formed in the bushing at the bearing surface between such bushing and said casing, and means for admitting bearing-cleansing fluid under pressure to said passages, whereby such fluid is caused to cool and lubricate the bearing assembly and to escape from said passages into the gases propelled through said housing.

7. Apparatus for propelling a gas that includes an abrasive or corrosive material comprising a housing having an inlet and an outlet for the gas to be propelled, two impellers mounted concentrically one within the other in said housing, a horizontal drive shaft, spider means supporting one impeller, the other impeller being secured to said shaft, two bearing assemblies for said shaft comprising two casings sealed to each of the opposite side walls of said housing, a hub portion extending from said spider means into each casing concentrically of said shaft, a bushing secured within said hub portion to provide

a bearing for said shaft, with the shaft-engaging surfaces of the bushings formed with passages communicating with the interior of said housing, a bushing secured externally upon each hub to provide in conjunction with said casing a bearing for said spider means, with passages formed in each bushing at the bearing surface between such bushing and said casing, and means for admitting bearing-cleansing fluid under pressure to said passages, whereby such fluid is caused to cool and lubricate the bearing assemblies and to escape from said bearing assemblies toward the opposite sides of said concentric impellers that propel the gas through said housing.

8. The structure of claim 7, said impellers being located between said bearing assemblies, and a plurality of spacer rings mounted on the shaft between the impeller and bearing assemblies, said passages being arranged to deliver

said liquid to said spacer rings, whereby liquid delivered inwardly through said passages is thrown centrifugally by said ring into the gas propelled by said housing.
